PLURAL COMPARTMENT TUMBLER TYPE
WASHING MACHINENorman S. McEwen, Fort Lauderdale, Fla., as-
signor to Helpy Selfy Service System, Inc., Fort
Lauderdale, Fla., a corporation of Florida

Application April 4, 1946, Serial No. 659,578

8 Claims. (Cl. 68—145)

1

This invention relates to washing machines of the rotating drum type, having for its object to provide a mechanism which is simple in construction and more efficient in operation than those heretofore proposed. More specifically the invention relates to washing machines comprising a drum which is of substantially regular polygonal shape having imperforate internal partitions creating a plurality of washing compartments, with means for supplying a washing liquid to each of said compartments through a portion of the shaft upon which the drum is mounted for rotation, and a dump valve for draining each compartment of its contained liquid.

In addition the invention comprises such a drum as above indicated wherein each partition extends from the center of the drum to a substantially median point of a peripheral side of the drum, with the dump valve disposed at the juncture of two peripheral sides, and linked reciprocable means carried by a stationary portion of the washing machine for opening and closing said valve, and the means for supplying the washing liquid to each of said compartments comprises a spider having a hollow hub portion carried by the drum shaft and surrounding a portion of said shaft, with hollow arms extending radially from the hub portion and secured to the drum for rotation therewith, an arm for each washing compartment.

With these and other objects in view the invention resides in the novel details of construction and combinations of parts as will be disclosed more fully hereinafter and particularly covered by the claims.

Referring to the accompanying drawings forming a part of this specification and in which like numerals designate like parts in all the views,

Fig. 1 is a vertical sectional view of a washing machine made in accordance with this invention, said view taken as on the line 1—1 of Fig. 2 and looking in the direction of the arrows;

Fig. 2 is a vertical section view of the parts shown in Fig. 1, said view taken as on the line 2—2 of Fig. 1 and looking in the direction of the arrows;

Fig. 3 is a detail view in section illustrating one means for operating a dump valve used in the washing machine; and

Fig. 4 is a detail elevational view of the dump valve, said view taken substantially on the line 4—4 of Fig. 3 and looking in the direction of the arrows.

The washing machine of this invention comprises in general a drum of regular polygonal

2

shape in accordance with the number of compartments desired (four being shown in the drawings), which drum is mounted on a horizontal shaft for rotation, each compartment of the drum being provided with an inlet for the soap solution for washing and/or clear water for rinsing the clothes, as well as an outlet controlled by a dump valve by means of which the liquid contents of a compartment may be discharged from the compartment. In order to furnish the liquids to the compartments, a portion of the shaft is provided with means for conducting the liquids to a spider, each arm of the spider leading to the inlet of a compartment. Any suitable means may be employed for rotating the shaft, and a casing surrounds the drum so that when the dump valves are open the liquids of the compartments may be expelled through the said valves under centrifugal action to be caught within said casing and permitted to escape therefrom through a suitable drain. Various advantages of this construction will become apparent as the detailed description and operation is studied.

More specifically a suitable framework is provided for supporting the washing machine, said framework on opposite sides being provided with bearings indicated at 2 within which the shaft generally identified by the numeral 3 rotates. The drum generally identified by the numeral 4 is securely mounted on said shaft, said drum in the drawings being illustrated as of square formation though it will be understood that other regular polygonal shapes may be provided, whereby said drum may be internally divided by partition walls to provide plural compartments, the four compartments illustrated herein being identified by the numerals 5, 6, 7 and 8, said partitions extending from the shaft to a substantially median point on one of the outer sides of the polygonal drum, in order that the dump valves for the compartments may be at the corners or vertices of the drum and hence at the outermost extremity of the compartment during rotation of said drum, this construction resulting in the maximum expulsion of a contained liquid from the compartments under centrifugal action while the drum is rotating and the valves are open. The dump valves are herein designated generally by the numerals 9, 10, 11 and 12, and the spider arms are designated by the numerals 13, 14, 15 and 16, with respect to the compartments 5, 6, 7 and 8.

The spider comprises a hub 20 secured to said shaft externally of the drum, said hub being hollow and having liquid communication with a

passage formed in an extension 21 of said shaft, which extension passes through a supplemental bearing 22 for rotation therein and terminates in a stuffing box 23 into which leads a fixed non-rotatable pipe connection 24 provided with a funnel-like open end 25 positioned to receive washing liquids from suitably valved supply pipes 26 and 27, one of said pipes adapted to furnish the washing solution and the other adapted to furnish hot and/or cold water, or a mixture thereof, as well understood in washing operations. The spider arms 13, 14, 15 and 16 are pipes extending radially from said hub to the vertices of the drum compartments as indicated in Figs. 1 and 2.

Upon said shaft extension 21 is secured a pulley 28 adapted to be driven as by a belt indicated at 29 from a pulley 30 mounted upon a shaft 31 receiving power through suitable speed-reduction gearing from a suitable source of power such as the electric motor indicated at 32 and carried by the framework of the washing machine, a suitable clutch also being provided as well understood in order to govern actuation of the drum through the power drive just described.

The casing of the machine comprises a fixed lower portion 33 of such shape as to permit the expelled liquids from the drum to gravitate to the discharge or drain 34. The rest of the casing comprises a hinged or removable upper portion 35, preferably of semicircular shape, against the inner surface of which the centrifugally expelled liquids may impinge and be directed by said surface downwardly into the lower portion 33 of said casing. Each compartment is provided with a suitable windowed door through which the clothes may be inserted and extracted, said door not being illustrated in the drawings, in the interest of simplicity, but well understood and having substantially liquid-tight engagement with a wall of the compartment.

The dump valve utilized in this washing machine is made substantially in accordance with the valve forming the subject matter of a co-pending application for patent by Norman S. McEwen filed May 2, 1945 under the Serial No. 591,477 and is particularly illustrated in Fig. 4. Said valve comprises a nipple 40 serving as the outlet for liquids from a compartment such as 5, said nipple having a head 41 attached to its outer end, said head having a laterally extending bracket 42 provided with a notch 43 into which fits the pointed fulcrum 44 of the valve arm 45.

One end of said arm carries a rubber washer 46 adapted to fit and close the open end of said head 41, the other end of said arm carrying a transverse pin or rod generally identified by the numeral 47, one end of which rod has the abutment 48 for a purpose that will appear hereinafter. Said arm 45 is bifurcated as clearly shown in Fig. 3 in order to fairly snugly straddle the bracket 42. The washer 46 is secured at its center to one side of said arm as by a screw 49, and substantially coaxial with said screw but extending from the opposite side of said arm is a post 50 for a purpose that will hereinafter be disclosed.

The bracket 42 at its lower end is provided with a suitable seat 51 for receiving the lower portion of a coil spring 52, the end portions of said spring extending curvilinearly upward over the arm 45 as indicated in Fig. 3, with the extreme ends of said spring engaging the post 50 as indicated at 53, said spring and notch 43 be-

ing so disposed, relative to each other, that when the valve is open, as indicated in full lines in Fig. 4, said spring will be to the right of said notch, and when the valve is closed, as indicated in dotted lines in said figure, said spring will be to the left of said notch, wherefore said spring will be seen to provide positive means for maintaining the valve under tension in either open or closed position.

Means are provided for opening and closing the valves, a practical means being illustrated in Figs. 3 and 4, and such means may be mounted on either the upper or lower portion of the casing as desired, though such mounting is illustrated in connection with the upper portion. Such means comprises a U-shaped bracket 60 secured to said casing as at 61 and 62, the legs of said bracket serving as bearings for a pair of push rods 63 and 64 extending through the wall of said casing and having on their outer ends the respective hand knobs 65 and 66 by means of which said rods are axially slid in said bracket. These rods are of a length such that their innermost ends are moved into and out of the paths of the pins 50 and the abutments 48 of the dump valves.

That is to say, when the rod 63 is moved inwardly with respect to the casing, its innermost end will be moved into the path of the dump valves to an extent to intercept the pins 50 thereof so that, when said pins strike the end of said rod, the dump valves will be actuated to open the same as clearly illustrated in Figs. 3 and 4. The position of rod 63 shown in Fig. 4 is at the instant that the pin 50 passes the same, at which instant it will be observed that the spring 52 lies to the right of the fulcrum notch 43 whereby the valve will be maintained in open position by said spring. When the rod 64 is moved inwardly with respect to the casing, its innermost end will be moved into the path of the dump valves to an extent to intercept the abutments 48 thereof so that, when said abutments strike the end of said rod, the dump valves will be actuated to close the same as clearly illustrated in said figures of drawings. The position of rod 64 shown in Fig. 4 is at the instant that the abutment 48 is struck thereby, causing a reverse pivotal movement of the valve arm 45 about its fulcrum to close the valve, in which pivotal movement the spring 52 will snap to a position to the left of the fulcrum notch and thus cause said spring to maintain the valve in its closed position.

Means are provided for insuring alternate simultaneous movements of the rods 63 and 64 so that when one rod is moved to its innermost position to actuate the valves, the other rod is automatically moved outwardly to an inoperative position with respect to said valves. Such a means may comprise a toggle 67 the ends of which engage notches such as 68 and 69 on the respective rods, said toggle having oscillatory motion by virtue of a pivot pin 70 operating at the center of said toggle, said pivot pin carried by an ear or lug 71 carried by said bracket 60 intermediate said rods 63 and 64. A spring indicated at 72 is provided between said bracket and said toggle and so mounted and positioned as to have snap-action to one side or the other of said pivot pin, whereby the rods 63 and 64 will be given simultaneous movement in opposite directions, and will be maintained in the positions to which they are moved. This is a well known construction and, from the showings in Figs. 3 and 4, the operation of said rods will be readily

understood. The rods are so spaced from each other that when one is in position to actuate the valves, the other will clear the portion of said valve which it is intended to operate, by virtue of the pivotal movement of the valve arm 45 which permits either its pin 50 or abutment 48 to be moved into striking positions relative said rods.

From the foregoing description it will be seen that by this invention there is provided a washing machine which is capable of handling, during one washing cycle, more clothes than has heretofore been possible, due to the provision of plural compartments. This increase in capacity is not merely the result of pluralizing the number of compartments, but additionally and very importantly due to the fact that this machine handles the wash in such manner that the machine may be said to be in balanced condition during such cycle. In other words, if the machine has four compartments as illustrated, and the total weight of the dirty clothes is 40 lbs., then said clothes are divided into four piles each pile weighing ten pounds, and a pile placed in each compartment so that the total weight of the wash is evenly divided during the rotation of the drum.

The necessary amount of washing liquid is admitted to each of the plural compartments through the spider arms, and the liquid level in each compartment observed through the windowed door thereof. Experience has shown that each compartment should be approximately one-third filled with liquid, but of course this amount may be varied in accordance with the quantity of clothes in the compartment. If desired, valves may be provided in the spider arms to regulate and maintain the quantity of liquid per compartment.

In the washing operation the dirty clothes are first weighed and then divided into as many piles as there are compartments, with substantially the same weight of clothes for each compartment. Then the dirty clothes are placed in the compartments with the necessary quantity of liquid, and power applied to rotate the drum for the washing stage. The speed of drum rotation for the washing need not be relatively great and the washing may be conducted for from ten to fifteen minutes, after which the dump valves are opened, and the speed of drum rotation increased if desired to lessen the time for draining the compartments of the dirtied wash liquid, after which said valves will be closed, the drum rotation stopped, and rinse liquid admitted to the compartments. Then the drum is again rotated at about the same speed as was given to it for the washing stage, the rinsing stage being conducted for about three minutes more or less, in accordance with the nature of the clothes being rinsed and the belief of the operator that the rinsing has been sufficient. Then the dump valves are again opened and the drum given a high speed of rotation, of the order of 1000 R. P. M., for the dry spin or extraction of the rinsing liquid from the clothes.

This relatively high rate of rotation of the drum can be practically accomplished with a minimum of vibration due to the balanced condition of the load of clothes in the plural compartments. Further, this high speed of rotation will extract the maximum amount of liquid from the clothes so that, at the end of the drying spin, the clothes may be withdrawn from the compartments and found to be in condition for im-

mediate ironing. The different rates of rotation of the drum for the washing and rinsing stages, as well as for the drying spin, can be accomplished by the provision of the aforementioned speed-reduction gearing and clutch or clutches. The complete cycle of washing, rinsing, and dry-spinning need not exceed thirty minutes, which is a distinct advantage, together with the balanced condition of the load, over washing machines heretofore known. Additionally, the polygonal shape of the drum, together with the partitions providing the plural compartments, result in the provision of plural angles which assist materially in the circulation, agitation and/or other movement of the clothes in each compartment, or in other words provide means for stirring the clothes in a compartment and preventing the usual "balling" of the clothes. This permits maximum contact of the liquid with the clothes during the rotation of the drum.

The dump valve illustrated and described is of course only one form of a practical valve for the purpose intended. An alternate dump valve could be one which was spring pressed against the outlet of a compartment, the tension of the spring utilized being calibrated so that the valve would not open at the relatively small centrifugal liquid pressures created during the speeds of the washing and rinsing stages, but would open under the increased and relatively great centrifugal liquid pressures created at a high (1000 R. P. M.) speed of rotation given for the dry spin, which high rate of rotation would also be given when washing and rinsing liquids were to be expelled from the compartment.

It is obvious that those skilled in the art may vary the details of construction and arrangements of parts without departing from the spirit of this invention, wherefore it is desired not to be limited to the exact foregoing disclosure except as may be required by the claims.

What is claimed is:

1. A washing machine comprising a drum of substantially regular polygonal shape having imperforate internal partitions creating a plurality of washing compartments, one compartment for each peripheral side of the drum, a shaft upon which said drum is mounted for rotation, means for supplying a washing liquid to each of said compartments through a portion of said shaft, means for rotating said shaft, and a dump valve for draining each compartment of its contained liquid.

2. A washing machine comprising a drum of substantially regular polygonal shape having radially extending imperforate internal partitions creating a plurality of washing compartments, a shaft upon which said drum is mounted for rotation, means for supplying a washing liquid to each of said compartments through a portion of said shaft, means for rotating said shaft, and a dump valve for draining each compartment of its contained liquid, said valve disposed intermediate two adjacent partitions.

3. A washing machine comprising a drum of substantially regular polygonal shape having internal partitions creating a plurality of washing compartments, one compartment for each peripheral side of the drum, each partition extending from the center of the drum to a substantially median point of a peripheral side thereof, a shaft upon which said drum is mounted for rotation, means for supplying a washing liquid to each of said compartments through a portion of said shaft, means for rotating said shaft,

and a dump valve for draining each compartment of its contained liquid.

4. A washing machine comprising a drum of substantially regular polygonal shape having internal partitions creating a plurality of washing compartments, one compartment for each peripheral side of the drum, each partition extending from the center of the drum to a substantially median point of a peripheral side thereof, a shaft upon which said drum is mounted for rotation, means for supplying a washing liquid to each of said compartments through a portion of said shaft, means for rotating said shaft, and a dump valve for draining each compartment of its contained liquid, said valve disposed at the juncture of two peripheral sides of the drum.

5. A washing machine provided with a supporting framework and comprising a drum of substantially regular polygonal shape having internal partitions creating a plurality of washing compartments, one compartment for each peripheral side of the drum, a shaft upon which said drum is mounted for rotation, means for supplying a washing liquid to each of said compartments through a spider secured to and rotatable with said drum, said spider having a hub surrounding a portion of said shaft, means for rotating said shaft, a dump valve for draining each compartment of its contained liquid, and means carried by the framework for opening and closing said valve.

6. A washing machine comprising a drum of substantially regular polygonal shape having internal partitions creating a plurality of washing compartments, one compartment for each peripheral side of the drum, a shaft upon which said drum is mounted for rotation, means for supplying a washing liquid to each of said compartments through a portion of said shaft, said means comprising a spider having a hollow hub portion carried by said shaft and a plurality of hollow arms extending radially from said hub portion, said arms secured to said drum for rotation therewith, an arm for each compartment, means for rotating said shaft, and a dump valve for draining each compartment of its contained liquid.

7. A washing machine comprising a drum of substantially regular polygonal shape having internal partitions creating a plurality of washing compartments, one compartment for each peripheral side of the drum, a shaft upon which said drum is mounted for rotation, means for supplying a washing liquid to each of said compartments through a portion of said shaft, said means comprising a spider having a hollow hub portion surrounding a portion of and carried by

5 said shaft, said spider further having a plurality of hollow arms extending radially from said hub portion, said arms secured to said drum for rotation therewith, an arm for each compartment, said hub portion having liquid conducting relationship with a duct formed in said shaft, said duct leading to a source of liquid supply, means for rotating said shaft, and a dump valve for draining each compartment of its contained liquid.

10 8. A washing machine provided with a supporting framework and comprising a drum of substantially regular polygonal shape having internal partitions creating a plurality of washing compartments, one compartment for each peripheral side of the drum, a drain for each compartment, a shaft upon which said drum is mounted for rotation, means for supplying a washing liquid to each of said compartments through a portion of said shaft, means for rotating said shaft, a dump valve for draining each compartment of its contained liquid, said valve disposed at the juncture of two peripheral sides of the drum, said valve comprising a closure member for the drain of the compartment, said member pivotally mounted upon an outer surface of such drain and provided with a spring encompassing a portion of said member and engaging said drain for securing said member to such drain, said member having a post disposed to one side and a lateral abutment disposed to the other side of the pivotal mounting of said member, the ends of said spring secured to said post, and manually operable means comprising a pair of linked oppositely reciprocable rods carried by the framework and movable alternately into the paths of said post and said abutment to be struck thereby for causing the pivotal movement of said member, one rod for causing opening movement and the other rod for causing closing movement of said valve closure member while said drum is rotating.
